LOCOMOTIVE SPRING SUSPENSION

Bernard F. Langer, Pittsburgh, Pa., assignor to
Westinghouse Electric Corporation, East Pittsburgh, Pa., a corporation of Pennsylvania

Application February 24, 1947, Serial No. 730,592

5 Claims. (Cl. 105—73)

1

My invention relates, generally, to locomotive spring-suspension systems and, more particularly, to spring suspensions for motorized locomotive tenders.

In locomotives for heavy freight service, the use of too many idle, non-powered axles is uneconomical because the starting tractive effort is limited by the weight on the drivers. In some steam locomotives tractive force is obtained from the axles on the tender by means of "boosters." In a recently proposed steam-turbine-electric locomotive, motors will be placed on some of the tender axles in order to obtain sufficient tractive effort.

In a tender having a spring equalization system of the conventional type there is a large variation in the axle load between the full and the empty conditions of the tender. Thus, if sufficient power is applied to the tender axles to make full use of the axle load when the locomotive starts its run with a fully loaded tender, the wheels on the tender axles will slip badly later on, when most of the fuel and water have been used.

An object of my invention, generally stated, is to provide a spring suspension for a motorized locomotive tender which shall be simple and efficient in operation and which may be economically manufactured and installed.

A more specific object of my invention is to reduce the variation in the load on the driving axles of a motorized locomotive tender as the tender load decreases from full to empty.

Another object of my invention is to increase the tractive effort of a motorized locomotive tender.

Other objects of my invention will be explained fully hereinafter or will be apparent to those skilled in the art.

In accordance with one embodiment of my invention, the variation in driver load on a tender which has some idle and some motorized axles is materially reduced by utilizing a spring suspension which causes the idle axles to lose more load than the driving axles as the tender empties. This may be accomplished by providing springs over the idle axles which are stiffer than the springs over the driving axles, thereby causing the variation in load on the idle axles to be greater than that on the driving axles.

For a better understanding of the nature and objects of my invention, reference may be had to the following detailed description, taken in conjunction with the accompanying drawing, in which:

2

Figure 1 is a view, in side elevation, of a locomotive and tender embodying the principal features of my invention.

Fig. 2 is an enlarged view, in side elevation of the locomotive tender, and

Figs. 3, 4 and 5 are diagrammatic views showing the spring deflections for various loads on a tender of the type illustrated in Figs. 1 and 2.

Referring to the drawing, and particularly to

10 Fig. 1, the locomotive shown therein comprises a power unit 10 and a tender 11. As shown, each axle of the power unit is provided with an electric motor 12, which may be of any type suitable for driving the axle. The power for the 15 motors 12 may be supplied by a generator, or generators, located in the power unit and driven by either a steam or a gas turbine or other suitable prime mover.

In accordance with the usual practice, the fuel 20 for the prime mover is carried in the tender 11. As explained hereinbefore, the tractive effort of the locomotive may be increased by providing traction motors 12 on some of the axles of the tender. However, in order to avoid slippage of the 25 driving wheels when the tender is lightly loaded, it is necessary to provide a spring suspension system different from the conventional system which distributes the load evenly on all points of support.

30 Thus, in the present structure, the normal variation in the load on the driving axles is materially reduced by providing motors for only part of the axles on the tender and by utilizing a 35 spring suspension system which causes the non-driving axles to lose more load than the driving axles as the load carried by the tender decreases.

As previously explained, such a system can 40 not be of the conventional "three point" type, but can be a system in which the stiffness of the springs over each axle affects the percent of the total load which the axle carries. Thus, if the springs over the idle axles of a partly motorized tender are stiffer than those over the driving 45 axles, the variation in load on the idle axles will be greater than that on the driving axles.

As shown in Fig. 2, the body of the tender 11 is carried on four swivel trucks 13, instead of on 50 two trucks as is the usual practice. The first and last trucks are motorized, each axle of these trucks being provided with an electric motor 12. As indicated, these trucks are provided with relatively soft springs 14 which may be of the leaf 55 type. The intermediate trucks are non-motorized

and are provided with relatively stiff springs 15 which may also be of the leaf type.

As shown, the springs on each truck may be suspended from equalizing bars 16 which span the two axles on that truck. However, there is no equalization between the different trucks, the spring suspension system on each truck being independent of the other trucks.

In the example shown in Figs. 3, 4 and 5, the load on each driving axle of a tender of the type illustrated and having soft springs with a scale of 17,850 lbs./in. and stiff springs with a scale of 48,900 lbs./in. varies from 66,000 pounds for a fully loaded tender as shown in Fig. 4 to 52,500 pounds when the tender is carrying $\frac{1}{4}$ of its load as shown in Fig. 5. If the tender were provided with a spring suspension system of the conventional type, the load on each driving axle would drop to 41,000 pounds as compared with the 52,500 pounds for the present system. The aforesaid tender weighs 528,000 lbs. fully loaded and 326,000 lbs. $\frac{1}{4}$ loaded. The unsprung weight of a motorized truck is 25,000 lbs. and non-motorized truck is 15,000 lbs., as shown in Fig. 3 in which it is assumed that the tender body is lifted off the trucks.

Thus, it will be seen that the variation in the load on the driving axles is materially reduced by utilizing a system of the present type. In this manner, the tractive effort of the locomotive may be materially increased, since the tendency of the driving axles to slip when the tender is lightly loaded is decreased, thereby permitting sufficient power to be applied to the driving axles to make practically full use of the axle load when the locomotive starts its run and the tender is fully loaded.

Since numerous changes may be made in the above-described construction, and different embodiments of the invention may be made without departing from the spirit and scope thereof, it is intended that all matter contained in the foregoing description or shown in the accompanying drawing shall be interpreted as illustrative and not in a limiting sense.

I claim as my invention:

1. In a locomotive tender, in combination, a plurality of non-driving trucks, a plurality of driving trucks having electric motors thereon, and independently suspended springs on each of said trucks for supporting unequal portions of

the tender load, the springs on the non-driving trucks being stiffer and deflected less from a non-loaded to a loaded condition than the springs on the driving trucks.

2. In a locomotive tender, in combination, a plurality of non-motorized trucks, a plurality of motorized trucks, and independently suspended springs on each of said trucks for supporting unequal portions of the tender load, the springs on the non-motorized trucks being stiffer and deflected less from a non-loaded to a loaded condition than the springs on the motorized trucks.

3. A locomotive tender comprising a body and a plurality of pairs of axles for supporting the body, part of said axles being non-driving and part of them being driving axles, and independently suspended springs for each pair of said axles, the springs for the non-driving axles being stiffer and deflected less from a non-loaded to a loaded condition than the springs for the driving axles.

4. A locomotive tender comprising a body and a plurality of trucks for supporting the body, part of said trucks being non-driving and part of them being driving trucks, and independently suspended springs on each of said trucks, the springs on the non-driving trucks being stiffer and deflected less from a non-loaded to a loaded condition than the springs on the driving trucks.

5. A locomotive tender comprising a body and a plurality of swivel trucks for supporting the body, part of said trucks being motorized and part of them being non-motorized, and springs on each of said trucks, the springs on each truck being independent of those on the other trucks, and the springs on the non-motorized trucks being stiffer and deflected less from a non-loaded to a loaded condition than the springs on the motorized trucks.
